UNITED STATES PATENT OFFICE.

JOHN F. WILMOT, OF DETROIT, MICHIGAN.

FOLDING BED.

No. 823,456.

Specification of Letters Patent.

Patented June 12, 1906.

Application filed April 22, 1905. Serial No. 256,902.

To all whom it may concern:

Be it known that I, JOHN F. WILMOT, a citizen of the United States, residing at Detroit, county of Wayne, State of Michigan, have invented a certain new and useful Improvement in Folding Beds; and I declare the following to be a full, clear, and exact description of the invention, such as will enable others skilled in the art to which it pertains to make and use the same, reference being had to the accompanying drawings, which form a part of this specification.

This invention relates to folding beds.

It has for its object an improved bed adapted to produce a three-ply fold of the mattress, with the folds across the mattress, whereby a full-length bed and a full-width bed may be used in connection with a seat into which the structure folds that is only as long as the bed is wide, thus enabling me to employ a structure which is only about four and one-half feet in length when the structure is used as a seat or settee and yet furnishes a bed which is six and one-half feet in length when the structure is unfolded and used for bedstead purposes.

In the drawings, Figure 1 is a side elevation of the unfolded structure. Fig. 2 is a longitudinal section of the folded structure. Fig. 3 shows the locking-pin used to lock the structure in its open position. Fig. 4 is a detail view showing the socket connection between the leg and the frame.

The main or base part of the bed is a rectangular box, preferably an iron framework, with the corner-posts 1 and 1^a rising above the cross-ties 2 2^a. The corner-posts are tied by side bars 3 3^a, to which are hinged the folding frames, which constitute the head extension. The foot extension is hinged to corner-posts 1^a. This foot extension constitutes the seat of the settee when the structure is folded to settee form. The head extension comprises the back of the settee and consists of a frame with side bars 4, with cross-ties at their ends. Each side bar 4 is curved at that end which lies toward the foot of the bed and at a proper point on the curved portion is connected by pivot-pins to an ear 31 on the side bar 3.

The end of the frame-bar 4 is pivoted to a link 41, that connects it to a bell-crank lever 5, which is pivoted to an ear 51 from the side bar 3^a. The bell-crank lever 5 is in turn pivoted to a spring-support 6, that supports a battery of springs under the middle part of

the mattress. The back vertical bar of the extension-frame joints the curved front bar 4 at the pivot 4^a. A board 8 is pivoted to the frame at its extreme end, folds down and forward and forms the back of the settee or folds up to form the head of the bed, and is supported by a hooked brace 81, pivoted to the headboard at pivot 82 and hooking over pin 83 on the side bar 4. A leg-support 9 is pivoted to a lug 171, that is secured to the side bar 7 and drops out against a stop-pin 172 when the extension is folded out. The pivot on which the leg turns passes through a slot in the leg, and the leg can slide on the pivot for a limited distance. The top end of the leg is thus held secure against any liability to fold when the bed is in use.

The foot extension comprises a frame with a rectangular base and with curved sides 11, 75 that form the support under the foot extension in the unfolded condition of the structure. The base is connected by links 13 to the spring-support 6 and is pivoted in such relation with the end to the intersection of 80 side bars 21 and 31 that the intersection turns around the pivot and reaches the top of the corner-post 1^a when the frame is in its unfolded condition. A frame with end bars 10, which contains the seat-support of the 85 settee, is pivoted to the curved bar 11 at 22 and is provided at its oscillating side with a pin 23, which engages in slot 24 and allows the frame, of which the bar 10 forms a part, to swing down away from the mattress-support when the frame is unfolded and allows it to swing to a level position, as shown in Fig. 2, when the structure is folded to the position it assumes when used for settee purposes. The slot 24 is not essential to this result, because if the frame with end bars 10 be fixed or for any reason fails to turn on its pivot the seat will still assume a horizontal position when in place as a seat and assume a 90 inclined position free from the mattress-supporting frame when the structure is unfolded. Preferably the frame which supports the settee-seat is shorter than the length across the structure, and this frame swings between the corner-posts 1^a. The 95 frame of the foot-section is shorter than the base-frame and in folded condition swing partly down into the base-frame, coming to rest with stop 32 engaging against bar 3. A footboard 14 swings on a pivot journaled in 100 an ear 15 and swings around the guide 17. In folded condition the footboard 14 swings

105

around the guide 17 and the catch 18 engages in notch 19 and the edge of the foot-board 14 engages with the edge of the head-board 8, the two together forming the back 5 of the settee.

An apron 20, hinged to the bottom cross-bar of the main frame, automatically swings forward and is pulled to a vertical position by springs 25 and closes in the front side of 10 the structure, concealing the inclosed mattress and all the inclosed working parts from view and protecting them from dust and dirt.

The mattress-support is flexible, preferably of woven wire or linked wire, secured to 15 a cross-bar of the frame near the hinged end of the seat-frame 10 and secured also to the head extension near the angular turn of the bar 7 directly below the intersection of that 20 bar and the tie which binds it to bar 4. It passes below the pivotal point through the ear 31 and below the pivotal point between the foot extension and the base-frame and is strongly strained by unfolding the structure. The bar 7 and the vertical bar 1 are 25 provided with perforations 71 and 72, through which is inserted or can be inserted a holding-pin 73, if it is desired to move the structure in its extended or unfolded condition. The bar 4 is pivoted with a hook 43, 30 that engages over pin 44 to hold the parts when the structure is closed up. When the structure is unfolded, the spring-support 6 is held up strongly against the mattress-support, and any weight placed upon the material tends to hold the structure open with no 35 tendency to close it up. When the structure is folded, the spring-support 6 is lowered and affords abundant room for mattress and 40 clothing.

In the foregoing description I have explained the embodiment of the invention as 45 preferably made from properly-shaped metal; but I do not wish to confine myself to that material, as the same ideas may be readily embodied in a structure made wholly or principally of wood.

What I claim is—

1. In a folding bed, having a base-section, 50 a foot extension adapted to fold over the base-section to form a seat, a head extension adapted to fold vertically to form the back to a seat, a folding headboard adapted to fold to face the back section, a footboard adapted to fold to form a partial facing to the back, substantially as described.

2. In a three-part folding bed, in combination with a webbing supported at its ends, a seat-frame secured to one of the folding sections and adapted to fold under the webbing and to swing away therefrom and to fold in a second position over said webbing, substantially as described.

3. In a folding bed, in combination with a 65 base, a folding foot extension adapted to fold

over the base and to fold out to a horizontal position at the foot end of the base, a seat-frame pivoted to the foot extension, means for limiting the swing of the seat-frame between a condition of entire clearance from 70 the mattress-support when on the under side of said mattress-support, and a substantially horizontal position when above said mattress-support, substantially as described.

4. In combination with the extension part 75 of a folding bed, a seat-frame hinged thereto, and a limiting-guide for said seat-frame, whereby the seat-frame automatically assumes a horizontal position in the folded condition, and an inclined position in the unfolded position of the extension, substantially as described.

5. In combination with the extension part 80 of a folding bed, a seat-frame attached thereto and adapted to assume a horizontal position in the folded condition, and an inclined position in the unfolded position of the extension, substantially as described.

6. In a folding bed, in combination with a base-section, a foot-section adapted to fold 85 over the base-section and provided with a seat-frame, means whereby the said seat-frame assumes a horizontal position in the folded bed, and assumes an inclined position free from the mattress in the unfolded bed, 90 substantially as described.

7. In a folding bed, in combination with a base-section and a foot-section adapted to fold as an extension thereto, a seat-frame pivoted in the foot-section with a swinging 95 edge provided with a pin which engages through a slotted part in the foot-section, whereby the said seat-frame is adapted to swing and is guided and limited in its swinging movement, substantially as described. 105

8. In a folding bed, in combination with a base-section, a foot-section adapted to fold over the base-section and to fold away therefrom as an extension thereto, an apron pivoted to the base-section near the lower edge 110 and on the side toward the foot-section thereof adapted to swing as the foot-section is opened out in extension of the base-section, and to close automatically on the reverse movement of the foot-section, substantially 115 as described.

9. In a folding bed, in combination with a base-section, a head-section adapted to fold to a horizontal extension of the base-section and to a vertical position to form a back 120 therewith, a headboard pivoted to the head-section adapted to partly cover the portion of the mattress and bedding contained in said head-section, and to be turned up to form a headboard when the head-section is extended, a footboard adapted to fold to cover the remainder of the mattress exposure, means for holding the headboard in vertical position with respect to the extended head-section, substantially as described. 125

10. In a folding bed, in combination with a base-section, a head-section adapted to fold to a horizontal extension of the base-section and to a vertical position to form a back therewith, a headboard pivoted to the head-section adapted to be turned up to form a headboard when the head-section is extended, a footboard adapted to form an extension of the headboard when the folded bed is in folded condition, means for holding the headboard in vertical position with respect to the extended head-section, substantially as described.
11. In a folding bed, in combination with a base-section, a foot-section adapted to fold as an extension thereto, a seat-frame pivoted in the foot-section and adapted to oscillate therein, and means for limiting the oscillation of said seat-frame, substantially as described.
12. In a folding bed, in combination with a base part, a foot extension provided with a seat-frame swinging with respect thereto and pivoted to fold over the base, a head extension pivoted to fold vertically over the rear of the base, a mattress-support held at its ends to the foot extension and the head extensions, means for straining the mattress-support, a spring-support under the mattress-support, links connecting the foot extension and the head extension to the spring-support and adapted to lift the spring-support and hold it in place under the mattress-support, substantially as described.
13. In a folding bed, having a base-section, a foot extension provided with a swinging seat-frame and being adapted to fold over the base-section to form a seat, a head extension adapted to fold vertically to form the back to a seat, a folding headboard adapted to fold to face the back section, a folding footboard adapted to swing into the same plane with said headboard, substantially as described.
14. In a folding bed, the combination of a base-section, a head extension adapted to fold from a vertical to a horizontal position, a folding headboard, a foot extension adapted to fold from a horizontal position over the base to a horizontal position at the foot of the base, a pivoted footboard adapted to swing to face the head-section, said headboard and footboard folding into the same plane, substantially as described.
15. In a folding bed, in combination with a base-section, a spring-support, a folding head-section pivoted to the base-section, a bell-crank lever adapted to actuate the spring-support, and a link connection between the end of the bell-crank lever and the folding head-section, substantially as described.
16. In a folding bed, in combination with a base-section, a foot-section adapted to fold over the base-section and to fold in extension with the base-section, a head-section adapted to fold vertically with respect to the base-section, and horizontally in extension therewith, a headboard, a footboard, means for securing the same in a vertical position with respect to the unfolded foot-section, and means for securing the same vertically in the folded condition in continuous plane with the headboard, substantially as described.
17. In a folding bed, the combination of a base-section, a foot-section adapted to fold over the base-section, a seat-frame pivoted to the foot-section, means whereby the seat-frame assumes a substantially horizontal position when above the base-section, and an inclined position when folded away from the base-section, substantially as described.

In testimony whereof I sign this specification in the presence of two witnesses.

JOHN F. WILMOT.
